UNITED STATES PATENT OFFICE.

FRANKLIN A. WHELAN, OF MOUNT VERNON, VIRGINIA.

DESIGN FOR A SPOON, FORK, OR SIMILAR ARTICLE.

41,815.

Specification for Design.

Patented Oct. 3, 1911.

Application filed July 3, 1911. Serial No. 636,733. Term of patent 7 years.

To all whom it may concern:

Be it known that I, FRANKLIN A. WHELAN, a citizen of the United States, residing at Mount Vernon, in the county of Fairfax and State of Virginia, have invented a new, original, and ornamental Design for a Spoon, Fork, or Similar Article; and I do hereby declare the accompanying drawing to be a full, clear, and exact illustration of the same, and which said drawing constitutes part of this specification, and represents a face view of a spoon, fork, or similar article embodying my design.

I claim:

The ornamental design for a spoon, fork or similar article, as shown.

FRANKLIN A. WHELAN.
